UNITED STATES PATENT OFFICE.

HERBERT W. CHENEY, OF MILWAUKEE, WISCONSIN, ASSIGNOR TO ALLIS-CHALMERS COMPANY, A CORPORATION OF NEW JERSEY.

MOTOR-CONTROLLER.

965,280.

Specification of Letters Patent.

Patented July 26, 1910.

Application filed October 25, 1909. Serial No. 524,351.

To all whom it may concern:

Be it known that I, HERBERT W. CHENEY, a citizen of the United States, residing at Milwaukee, in the county of Milwaukee and State of Wisconsin, have invented certain new and useful Improvements in Motor-Controllers, of which the following is a full, clear, and exact specification.

My invention relates to starting controllers for electric motors, and more particularly to fool-proof potential starters for polyphase induction motors.

In operating starting devices for some types of motors, especially potential starters for induction motors, it is often undesirable that the controller be moved backward from a running to the starting position. To this end controllers have been designed which move directly from the running to the off position without passing through the starting positions. Also, it is often desirable that it be impossible to leave a controller in a starting position. For instance, in potential starters for induction motors, in various windings which are connected in circuit when the controller is in a starting position are proportioned to carry current not continuously but only for a brief period during starting. It may also be desirable to have means whereby upon certain abnormal conditions, such as "no voltage" or an overload, the controller is automatically moved from running to off position. These things are all accomplished by the controller shown in my Patent 916,843, granted Mar. 30, 1909.

It is the object of my present invention to simplify the construction shown in the aforesaid patent, and yet to lose none of the benefits obtained by the arrangement shown in such patent.

The various novel features of my invention will appear from the description and drawings, and will be particularly pointed out in the claims.

Figure 1 is a side elevation of a controller embodying my invention, some of the parts being shown in section; Fig. 2 is an end elevation of the controller of Fig. 1, with the front cover removed and the controller in off position; Figs. 3 and 4 show parts of the operating mechanism in starting and running position respectively; Fig. 5 is a development of the notched ring on the front cover of the controller; and Fig. 6 is a diagram of the electrical connections.

The details of the starting controller proper will not be fully described herein because they form no part of the present invention and are unnecessary to an understanding thereof.

The three-phase induction motor M is supplied with current from three-phase mains f, g, and h. When the controller is in off position the motor is entirely disconnected. When the controller is in starting position the auto-transformer windings 12 and 12^a, which are within the casing 13, are each connected between the two of the mains, the main h being connected to one terminal of each winding. One of the terminals of the motor M is connected to those two terminals of the windings 12 and 12^a which are connected in common to the main h, and the other two motor terminals are connected to intermediate points on the auto-transformer windings 12 and 12^a respectively. The windings 12 and 12^a thus constitute in effect a single V-connected auto-transformer, the main h and the middle terminal of the motor being connected to the middle of the V. When the controller is in running position the auto-transformer windings 12 and 12^a are entirely disconnected, and the motor terminals are connected to the three mains respectively. In the controller shown there is but one starting position between off and running position, but it is obvious that any desired number of such starting positions may be employed.

The normal operation of the controllers is always in the same direction, a movement through 180° constituting a complete operation. The controller drum 14, which is immersed in oil in the tank 15, is moved by the operating handle 16 through the gear wheels 17 and 18. The opposite halves of the controller drum are identical in structure, and each half cooperates in turn with each of two sets of contact fingers during successive operations of the controller, the sets of contact fingers being on opposite sides of the drum and arranged simultaneously to contact with the two halves of the drum respectively.

Fixed on the shaft 19, which carries the gear 18 and the handle 16, are a cam wheel 20 and a mutilated gear 21. This cam wheel and gear may be parts of the same casting, if desired. A member 22, pivoted on a pin 23, is provided with gear teeth which at 110

2 certain times mesh with the teeth of the gear 21, and with a roller 24 which at certain times rides on the periphery of the cam wheel 20. The member 22 is biased, as by 5 a spring 25, in a clockwise direction to the position in which it is shown in Fig. 2. An arm 26, pivoted on a pin 27, is the armature of a "no voltage" magnet 28, connected across two of the motor leads. The arm 26 10 is biased toward the no voltage magnet 28, as by a spring 29, and carries a roller 30 which at certain times engages the cam wheel 20 to prevent clockwise movement thereof. In the circuit of the no voltage 15 magnet 28 may be connected one or more normally closed switches 31. The solenoid or solenoids 32 of these magnets are connected in one or more of the motor leads so that they are responsive to an overload 20 on the motor when the controller drum 14 is in running position. On the front cover 33 of the controller casing is a notched ring 34, the notches of which are best shown in the development of Fig. 5. The ring 25 operates with a spring-pressed plunger 35 mounted in the handle 16 to prevent backward movement of the controller from off and running positions and to accentuate the starting positions.

30 When the controller is in off position the parts are as shown in Figs. 1, 2, and 6. The roller 24 is in engagement with the notch 36 of the cam wheel 20, and through such engagement backward movement of the controller is prevented. Backward movement is also prevented by the tooth of the notched ring 34 at off position. By moving the handle 16 substantially 60° in a clockwise direction, the starting position, illustrated in Fig. 3, is reached, and the motor is connected to the supply circuit through the auto-transformer windings 12 and 12^a. The operator feels when this starting position is reached on account of the engagement of the plunger 35 with the incline of the notched ring 31 at the starting position. As the controller is moved from off to starting position the member 22 is forced in a counter-clockwise direction against the action of the spring 25. 45 This movement of the member 22 is caused at first through the engagement of the notch 36 and roller 24 and later through the engagement of the teeth of the mutilated gear 21 with those of the member 22, these teeth 50 having been brought into engagement during the early part of the rotation of the members 20 and 22. Should the operator release the handle 16 with the controller in this starting position, the spring 25 will 55 move the member 22 in a clockwise direction, and through such movement will cause the handle 16 and controller drum 15 to be returned to off position. Thus it is impossible 60 for the controller to be left in starting 65 position without attention.

If the operator does not release his grasp on the handle 16 while the controller is in starting position, but when the motor has gained sufficient speed moves the handle substantially 60° farther in a clockwise direction, the controller is brought to running position, as shown in Fig. 4. This movement of the drum disconnects the auto-transformer windings completely and connects the motor terminals directly to the supply mains. As the handle 16 is moved from starting to running position, the member 22 is moved farther in a counter-clockwise direction against the action of the spring 25, this movement being obtained first by the 70 gear teeth on the gear 21 and member 22 and later by the cam surface 37 and roller 24. This roller passes over the point 38 of the cam wheel just before running position is reached. By means of the spring 25 and 75 member 22, the controller is thus biased backward to off position until just before the running position shown in Fig. 4 is reached, and will be moved backward to such off position if the operator releases his 80 grasp on the controller handle at any time before roller 20 has passed over the point 38. Backward movement of the controller from running position is prevented by the tooth 85 of the notched ring 34 at such position. 90

95 When the controller is fully in running position, the roller 24 engages the cam surface 39 of the cam wheel 20, and the spring 25 biases such wheel, and through it the controller drum, forward to off position. This 100 bias, however, is prevented from moving the controller because of the engagement of the outer end of the cam surface 37 with the roller 30, which is held in the position shown in full lines in Fig. 4 by the no voltage magnet 28. Should no voltage conditions prevail in the supply circuit for the motor, or should the motor take excessive current and cause the opening of any one of the switches 105 31, the magnet 28 is deenergized, and the 110 spring 25 acting through the roller 24 and cam surface 39, overcomes the spring 29 and moves the controller forward to off position. The controller may be moved manually forward from running position to off position 115 by applying a little force to the controller handle 16 and thus overcoming the pull of the magnet 28 on the arm 26. Whether the movement of the controller from running 120 position to off position is obtained manually or automatically, the roller 24 slides down the cam surface 39 to the notch 36^a and does not strike a hammer blow. This is found to be of considerable advantage both in lessening the noise of operating and in eliminating the shock to the controller. When the controller reaches off position it is prevented from being moved backward to running position by the tooth at the off position on the 125 notched ring 31. 130

The cycle above described may now be repeated, the two ends of the cam wheel 20, the two ends of the mutilated gear 21, and the two halves of the controller drum being 5 interchanged.

Many modifications may be made in the precise arrangement herein shown and described, and all such which do not involve a departure from the spirit and scope of my 10 invention I aim to cover in the following claims.

What I claim as new is:

1. In a controller, a rotatable drum, an operating handle therefor, a gear and a cam 15 wheel mechanically connected to the drum, and a spring which acts at times through the cam wheel and at times through the gear to bias said drum backward when in a starting position and forward when in running 20 position.

2. In a controller, a rotatable drum, an operating handle therefor, a gear and a cam wheel mechanically connected to the drum, a spring which acts at times through the 25 cam wheel and at times through the gear to bias said drum backward when in a starting position and forward when in running position, and means for normally preventing such bias from being effective when the 30 drum is in running position.

3. In a controller, a rotatable drum, an operating handle therefor, a gear and a cam wheel mechanically connected to the drum, a spring which acts at times through the 35 cam wheel and at times through the gear to bias said drum backward when in a starting position and forward when in running position, and a latch for normally holding the drum against forward movement when 40 it is in running position.

4. In a controller, a rotatable drum, an operating handle therefor, a gear and a cam wheel mechanically connected to the drum, a spring which acts at times through the 45 cam wheel and at times through the gear to bias said drum backward when in a starting position and forward when in running position, a latch for normally holding the drum against forward movement when it is 50 in running position, and means for rendering said latch operative only upon the absence of predetermined abnormal conditions.

5. In a controller, a controller drum having off, starting, and running positions, a 55 cam wheel and a gear mechanically connected to said drum, a spring-pressed member which cooperates with said cam wheel and gear to bias the drum backward to off position when it is in any starting position and 60 to bias the drum forward to off position when it is in running position.

6. In a controller, a controller drum having off, starting, and running positions, a 65 cam wheel and a gear mechanically connected to said drum, a spring-pressed member

which cooperates with said cam wheel and gear to bias the drum backward to off position when it is in any starting position and to bias the drum forward to off position when it is in running position, and a latch 70 for normally holding said drum against forward movement from running position.

7. In a controller, a controller drum having off, starting, and running positions, a cam wheel and a gear mechanically connected to said drum, a spring-pressed member 75 which cooperates with said cam wheel and gear to bias the drum backward to off position when it is in any starting position and to bias the drum forward to off position when it is in running position, a latch for normally holding said drum against forward movement from running position, and a no-voltage magnet which when energized 80 renders said latch operative.

8. In a controller, a controller drum having off, starting, and running positions, a cam wheel and a gear mechanically connected to said drum, a spring-pressed member which cooperates with said cam wheel and gear to bias the drum backward to off position when it is in any starting position and to bias the drum forward to off position when it is in running position, a latch for normally holding said drum against forward movement from running position, a no-voltage magnet which when energized 85 renders said latch operative, and means for causing the deenergization of said magnet upon an overload.

9. In a controller, a drum having off, starting, and running positions and normally movable always in the same direction, means for preventing backward movement of the drum from the off and the running 105 positions, a cam wheel and a gear, and a spring-pressed member which cooperates with said cam wheel and gear to bias said drum backward to off position when it is in any position from which it may be moved 110 backward and to bias it forward to off position when it is in running position.

10. In a controller, a drum having off, starting, and running positions and normally movable always in the same direction, 115 means for preventing backward movement of the drum from the off and the running positions, a cam wheel and a gear, a spring-pressed member which cooperates with said cam wheel to bias said controller backward 120 to off position when it is in any position from which it may be moved backward and to bias it forward to off position when it is in running position, and means for preventing such bias from being effective when the 125 drum is in running position.

11. In a controller, a drum having off, starting, and running positions and normally movable always in the same direction, 130 means for preventing backward movement

- 4
- of the drum from the off and the running positions, a cam wheel and a gear, a spring-pressed member which coöperates with said cam wheel and gear to bias said controller backward to off position when it is in any position from which it may be moved backward and to bias it forward to off position when it is in running position, means for preventing such bias from being effective 5
- 10 when the drum is in running position, and means for rendering the last mentioned means inoperative upon abnormal conditions.
12. In a controller, a drum having off, 15 starting, and running positions and normally movable always in the same direction, means for preventing backward movement of the drum from the off and the running positions, a cam wheel and a gear, a spring-pressed member which coöperates with said 20 cam wheel and gear to bias said controller backward to off position when it is in any position from which it may be moved backward and to bias it forward to off position
- 25 when it is in running position, means for preventing such bias from being effective when the drum is in running position, and means for rendering said last mentioned means inoperative upon no-voltage or over- 30 load.
13. In a controller, a controller drum nor-

mally movable always in the same direction and having off, starting, and running positions, means for biasing said drum backward to off position when it is in a starting 35 position and forward to off position when it is in running position, a magnet connected across the supply circuit, and means operative while such magnet is energized for preventing the aforesaid bias from being 40 effective when the controller is in running position.

14. In a controller, a controller drum normally movable always in the same direction and having off, starting, and running positions, means for biasing said drum backward to off position when it is in starting 45 position and forward to off position when it is in running position, a magnet connected across the supply circuit, means operative 50 while such magnet is energized for preventing the aforesaid bias from being effective when the controller is in running position, and a switch in the circuit of said magnet which is opened upon an overload. 55

Milwaukee, Wis., Sept. 28, 1909.
In testimony whereof I affix my signature,
in the presence of two witnesses.

HERBERT W. CHENEY.
